DESIGN FOR A WING NUT

David J. Biller, St. Louis, Mo., assignor to Day-Brite Lighting, Inc., St. Louis, Mo., a corporation of Missouri

Application June 13, 1942, Serial No. 107,188

Term of patent 14 years

To all whom it may concern:

Be it known that I, David J. Biller, a citizen of the United States and a resident of the city of St. Louis and State of Missouri, have invented a new, original, and ornamental Design for Wing Nut, of which the following is a specification, reference being had to the accompanying drawing, forming part thereof.

Fig. 1 is a rear view of a wing nut, showing my new design,

Fig. 2 is a front view of said wing nut,

Fig. 3 is a side elevational view of said wing nut, showing the wings in side elevation,

Fig. 4 is a side elevational view of said wing nut, showing one of said wings in end elevation; and

Fig. 5 is an axial section on the line 5—5 in Fig. 3.

I claim:

The ornamental design for a wing nut, as shown.

DAVID J. BILLER.
